UNITED STATES PATENT OFFICE.

FREDERICK L. MCGAHAN, OF LOS ANGELES, CALIFORNIA; VIOLA K. WALKER, ADMINISTRATRIX OF SAID FREDERICK L. MCGAHAN, DECEASED, ASSIGNOR TO THE PURPOSED MIND DEVELOPMENT SECURITY ASSOCIATION OF THE WORLD, A TRUST COMPANY.

SMOKE COLLECTOR AND CONDENSER.

Application filed June 16, 1919. Serial No. 304,450.

To all whom it may concern:

Be it known that I, FREDERICK L. MCGAHAN, a citizen of the United States, residing at the city of Los Angeles, in the county of Los Angeles and State of California, have invented certain new and useful Improvements in Smoke Collectors and Condensers, of which the following is a specification.

10 This invention relates to cinder and spark disposing means, particularly as applied to locomotives; reference being especially directed to the prior Patent No. 1,292,399, dated Jan. 21, 1919, issued to this same inventor for a locomotive.

In the accompanying drawing forming part of this specification, in which like numbers of reference denote like parts wherever they occur, Fig. 1 is a vertical sectional view through the smoke collector and condenser, taken on line 1—1 in Fig. 10; Fig. 2 is a transverse sectional view through the locomotive fire box, taken on line 2—2 in Fig. 11; Fig. 3 is a transverse horizontal section through the smoke collector, taken on line 3—3 in Fig. 1; Fig. 4 is a vertical longitudinal sectional view approximately on the line 4—4 of Figure 6 illustrating part of the apparatus for disposing of cinders and sparks; Fig. 5 is a detailed view of the spark arrester; Fig. 6 is a vertical sectional view of the spark-disposing apparatus, taken on line 6—6 in Fig. 4; Fig. 7 is a horizontal section through the rear part of the locomotive, taken on line 7—7 in Fig. 8; Fig. 8 is a side elevation of the rear part of the locomotive, showing the fire box in section; Fig. 9 is a vertical sectional view through the smoke collector 40 fan, taken on line 9—9 in Fig. 10; Fig. 10 is a horizontal section of the same taken on line 10—10 in Fig. 1; Fig. 11 is an elevational view of the complete locomotive, showing the relative arrangement of the various parts; and Fig. 12 is a detailed view of an internal valve of the smoke collector.

The locomotive 30 has cabs 31 and 32 at its front and rear ends, respectively. Cab 32 is mounted on the tender 26 and may be partitioned off from the fuel chamber of the latter by any suitable means, such as by a partition 33. The fire box 6

of the locomotive is provided in a suitable space 34 and in front of the fire box is the main boiler 36 having fire flues 27 leading from the fire box to the chamber 37, which in turn connects with a passage through the upper boiler 38 to the smoke stack 39. The smoke, gases and cinders will be diverted from the smoke stack 39 by passing the same from the chamber 37 through the pipe 5 into the fan chamber 7 of the turbine, from whence they are drawn by the fan 1 into the inner chamber 9 of the turbine 3, located at the front end of the boiler 36.

The conical rotor 40 of the turbine 3 is hollow-cast of shell shape and is rigidly secured by a key or other means at its smaller diameter to the turbine shaft 2 by means of hub 41. The said rotor 40 bears on the thrust-balls 42 operating in ball-race 43 and groove 44. Ball-race 43 is conveniently secured to pedestal 45, and the pedestal is bolted to cup 46 of the conical stator or outer shell 47 of the turbine. Rotor compression blades 48 are helical in form and of any desired pitch. These blades are held against the highly ground surface of the shell 47 at 49 by means of flat zigzag springs 50 which are tempered to hold blades 48 in position against the said surface.

Fan 1 and plate 54 are suitably secured to the shaft 2. Fan 1 is fixed on the fan plate 54 and the latter is borne by conical rollers 55 mounted on the race 56 of the cylinder 47 in any common manner. Fan plate 54 has orifices 8 through which the smoke, cinders, sparks, and soot are drawn into the chamber 9. The exhaust steam from the driving cylinders 57 of the locomotive passes by way of pipes 58 to the box 59, and thence through pipe 4 to the turbine chamber 11. From chamber 11 the steam is admitted into chamber 9 through as many valves 60 as will be found desirable. Valves 60 are opened by trippers 61 of the governor plate 53 striking against lever 62 when the said governor plate 53 is lowered by the collapsing of the governor balls 71 whenever the speed of the governor is decreased. Lever 62 is fulcrumed and pinned to rotor 40 at 64 and the other end of the lever is pivoted to

the valve rod 65 at 66. Valve rod 65 is pivoted to valve 60 at 67, the said valve being fulcrumed at 68 to the rotor 40 as shown in Figs. 1, 3 and 12. Valve rod 65 preponderates in weight, tending to keep valve 60 closed.

The action of the governor 52 is the same as the common fly-ball governor; the arms 70 which carry the balls 71 being pivotally connected at 73 to the upper collar 72, which is fixed to the shaft 2. Links 74 connect arms 70 to the lower sliding collar 63. Governor plate 53 is fixed to sliding collar 63, which causes the former to be rotated at the same speed as shaft 2 and, when the centrifugal force of the revolving balls 71 becomes great enough, they fly outwardly and raise the lower sliding collar 63. The said collar being fixed to valve plate 53 causes trippers 61 to rise, permitting levers 62 to tilt because of the predominating weight of the rods 65, which rods are lowered and the valves thereby closed. Trippers 61 project from plate 53 so that levers 62 may be clear of plate 53. Valve 69 is actuated in the same manner as valve 60, by the ascending and descending motion of the valve plate 53, as determined by the action of the governor 52. All gases, cinders, sparks and soot pass into chamber 9 through valve 60 and are condensed by the revolving and churning motion which takes place therein, to be subsequently discharged through valve 69 and further mixed with steam as it passes through exhaust pipe 12 of the turbine to be carried to the strainer or spark arrester 13, as hereinafter described. The object of the governor 52 is to regulate the suction 40 of the fan 1; when the speed of the fan increases, the valves 60 and 69 decrease the respective openings which they control, and when the speed of the fan decreases, the said openings are increased by the said 45 valves, so that any increased suction of the fan 1 is compensated for by the increased resistance to the flow of smoke and gases through the valve 69 and of steam through the valve 60. The steam necessarily parts with some of its inherent kinetic energy when impinging against the blades 48 to rotate the rotor, and the pressure of the steam, therefore, manifestly decreases in its downward passage through the 50 turbine, the pressure at the valve 60 being greater than the pressure of the gases within the rotor, and the pressure of the steam at the valve 69 being less than the pressure of the gases within the rotor, whereby the 55 said valves function as inlet and outlet valves respectively.

To prevent leakage of steam around shaft 2, an annular packing gasket 75 is held against the annular flange 76 of the 60 rotor 40 by means of springs 77. Ball-

race 78 is secured to cup 46, shaft 2 revolving through both. Ball-race 79 is fixed on the truck support 80, and balls 81 roll in between races 78 and 79 in the usual manner. The function of these balls 81 is to produce a minimum of friction at this point, as this is the pivotal center of the wheel truck 82. Bevel gearing 83 is used to drive the truck wheels 84, the said gearing, however, forming no part of the present invention.

Pipe 12 contains the spark arrester 13 for stopping the cinders, etc. preparatory to their deposit through hopper 18 upon screw conveyor 19 which carries the cinders back to fire box 6. The cinders, stopped by the spark arrester 13 drop upon paddles 15 of the elevator 16 and are carried up around wheel 88 and emptied into the chute 17 from whence they descend through hopper 18 into the conveyor 19 where they are mixed with fresh fuel and driven, by the rotation of screws 20, through flexible coupling 21 and telescoping pipes 22 and 23 and through nozzles 24 into fire box 6. Elevator 16 comprises upper pulley 88, lower pulley 89, and intermediate idler or tightening pulley 90, around which passes the belt 91 carrying paddles 15 which extend across the casing wall 92 during their ascent through the elevator casing. Upper pulley 88 is fixed to shaft 94.

The construction and operation of the invention will be plain from an inspection of Fig. 11. Steam passes from boiler 36 through the driving cylinders 57 into pipe 58, box 59, and pipe 4 to turbine 3, which drives the fan 1 and thus draws the smoke, cinders, and other products of combustion from fire box 6 through the fire tubes 27, chamber 37, and thence through the pipe 5 into chamber 9, as shown by dotted arrows in Fig. 11. From the turbine 3 the steam, smoke, and gases pass through pipe 12 to the spark arrester 13 and elevator 16, where the sparks, cinders, and other solids are returned through hopper 18 to the screw conveyor 19, which returns them together with more fuel to the fire box 6 in the manner hereinbefore described. The steam from which the cinders, sparks, etc. have been separated passes out through the pipe 14 to drive the turbine 85 which propels the truck wheels 86 through suitable gearing, and the said wheels 86 in turn are connected through gearing 87 to operate the screw conveyor 20. The steam passes from turbine 85 for final disposition in a manner not forming a part of this invention.

By this arrangement, the objection of smoke escaping into the air is obviated; dangerous sparks are prevented from issuing into the atmosphere and causing accidents or fires; and cinders are returned

as fuel to the conveyor 19, which conveyor is normally acting to drive into the telescoping pipes 22 and 23, and through nozzles 24 into the fire box 6, the fuel that falls thereon through slots 25 in the tender 26, as will be understood from Fig. 7 of the drawings.

What is claimed is:

In a locomotive, the combination of a fire box, a turbine having a hollow conical rotor, steam pipes leading from the driving cylinders of the locomotive and arranged to direct steam against the said rotor for imparting rotary motion thereto, an exhaust pipe leading from said turbine, a spark arrester in said exhaust pipe, suction means located adjacent to the said turbine and actuated thereby, there being an opening between the said suction means and the interior of the said turbine, a conduit leading from the said fire box to the said suc-

tion means whereby sparks, cinders, smoke and other products of combustion are drawn into the interior of the said hollow rotor, the wall of the rotor having openings there-through, valve for said openings; governor-actuated means for controlling the opening and closing of the said valves during the operation of the said turbine, and means associated with the said exhaust pipe for removing the products of combustion, cinders, sparks or other solid particles therefrom, said means including a conveyor located adjacent the said spark arrester, a return conveyor leading back to the fire box, and means for effecting transfer of the said products, from the said first conveyor to the said return conveyor.

In testimony whereof I hereunto affix my signature.

FREDERICK L. McGAHAN.
